GALE L. FERGUSON, OF CLEVELAND, OHIO, ASSIGNOR, BY MESNE ASSIGNMENTS,
TO AUTO PRIME PUMP COMPANY, OF CLEVELAND, OHIO, A CORPORATION OF OHIO

PUMPING APPARATUS

Application filed December 12, 1927. Serial No. 239,368.

The present invention, as indicated, relates to pumping apparatus and has for its primary object the provision of a unitary device including a pump which will operate to maintain a storage reservoir in substantially filled condition and which is provided with connections whereby the water in the storage reservoir is used to supply the requirements of a service line, and in which fresh water, as distinguished from stored water, may be immediately and certainly supplied through a third connection. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

The single figure is a fragmentary sectional view of one form of apparatus designed to accomplish the above ends.

In said figure the reference numeral 1 indicates a pump casing providing a pump chamber 2 and a priming chamber 3, said pump chamber being adapted to receive pumping apparatus 4 and being provided with an inlet conduit 5 and an outlet conduit 6. The priming chamber 3 is suitably connected with inlet conduit 5. The outlet conduit 6 is divided into 3 branches, namely a storage branch 7, a service branch 8, and a fresh water branch 9.

A storage reservoir 10 which may assume practically any form, is suitably connected to the storage branch 7 by screws 11 or similar fastening means, and a conduit 12 provides communication between said branch 7 and said reservoir 10. The service branch 8 is screw-threaded at 13 for the reception of pipe connections, and the fresh water branch 9 is similarly threaded as at 14 for the reception of suitable pipe connections.

The branches 7 and 8 are arranged to be in constant communication with each other, but the casing is provided with an annular shoul-

der 15 screw-threaded as at 16 for the reception of a valve organization 17 adapted to separate said branches 7 and 8 from the fresh water branch 9 when such separation is desired. The valve organization 17 comprises a ring 17' provided with external threads for cooperation with the threads 16 and provided on its upper periphery with lugs 18 for engagement by a wrench. Said ring 17' affords on its upper surface a valve seat 19, and said ring is formed with a spider 20 terminating in a block 21 provided with a central bore 22 for the reception of a valve stem 23. The valve stem 23 is slidably mounted in the bore 22 and carries at its upper end a valve 24 for cooperation with the seat 19, and a pin 25 extends through the lower end of said valve stem and supports a washer 26 of suitable soft material for limiting the upward movement of the valve stem. The valve 24 is biased toward a closed position by gravity.

In the fresh water branch 9 there is provided a lateral port 27 to which is connected a pipe 28 leading to a pressure responsive switch 29. This switch may take any desired form, and is a well known device, and consequently it is believed unnecessary to describe or show the specific details thereof. Consequently the switch 29 is shown quite diagrammatically and conductor leads 30 are indicated as extending from a source of electrical energy while conductor leads 31 are indicated as extending to the motor (not shown) for operating the pumping mechanism 4.

The operation of the device is as follows:

When the apparatus is first installed, the motor circuit is closed manually and the pump is thus operated to force liquid into the outlet conduit 6. Presuming that all valves in the fresh water and service lines are closed, the pressure in the fresh water line will immediately build up to such a value as to open the valve 24 but not to such a value as to operate the switch 29. The valve 24 being open, liquid will flow in three directions; i. e., to fill the fresh water line, to fill the service line, and to fill the storage reservoir 10. As long as the pump is operating, the pressure in the fresh water branch 9 will be slightly higher than the pressure in the serv-

ice line and in the storage reservoir, since the valve 24 has a very slight throttling effect. Consequently said valve 24 will remain open until such time as the pressure in the three branches is built up to the optimum value. At such time the pressure in the fresh water branch 9 will operate on the switch 29 to break the motor circuit and stop the operation of the pump. As soon as the operation of the pump ceases, the pressures in the three branches attempt to equalize, and as soon as such pressures are equalized, the gravity bias of the valve 24 will close such valve. If, now, a valve in the service line is opened, liquid will flow from the storage reservoir 10 to replace the liquid drawn through such valve. The pressure in the branches 7 and 8 is thus reduced below the pressure in the branch 9 and the pressure in the branch 9 therefore opens the valve 24. If sufficient water is drawn through the service line, the pressure in the branch 9 will drop sufficiently to cause actuation of the pressure responsive switch 29 to close the motor circuit and initiate operation of the pump once more. When the pressure has been again built up to the desired value, the switch 29 will again break the motor circuit. It will be understood that the arrangement herein shown and described is such as to cause a considerable lag between a reduction of pressure in the service and storage branches 8 and 7 respectively and the actuation of the switch 29. If, on the other hand, a valve in the fresh water line is opened, there is an immediate substantial reduction in the pressure in the fresh water branch 9, since the valve 24 remains closed to prevent replacement of any of the liquid in the fresh water branch 9 by liquid held in the storage tank. Consequently the switch 29 will be actuated almost simultaneously with the opening of a valve in the fresh water line, and operation of the pump will immediately be initiated. If the fresh water valve is opened very slightly, the pump will force more liquid into the outlet conduit than can flow through the fresh water valve, and the pressure in the fresh water line will thus be raised to such a value as to cause the switch 29 to break the motor circuit. Thus a slight opening of a valve in the fresh water line will cause repeated alternate operation of the switch 29. Since, however, the pressure in the branches 7 and 8 is substantially that pressure which will cause actuation of the switch 29 to break the motor circuit, and since the valve 24 is under a gravity bias toward closed position, there will never be a time when opening of a valve in the fresh water line will cause the valve 24 to be opened. Consequently, all probability of a flow of stored water through the fresh water line is obviated by the present arrangement.

65 The advantages of the present invention

will be quite obvious without more than a casual mention thereof. It will be readily understood that units of the type herein disclosed are intended primarily for domestic use in locations where "city water" is not supplied. Under such circumstances, it is, of course, desirable to have a quantity of stored liquid ready for emergency use. On the other hand, water which has been stored for several days in a tank is not desirable for drinking purposes. According to the present invention, then, the stored water will be used for toilet purposes, and separate outlets will be provided in the fresh water line for a supply of drinking water.

80 Other modes of applying the principle of my invention may be employed instead of the one explained, change being made as regards the mechanism herein disclosed, provided the means stated by any of the following claims or the equivalent of such stated means be employed.

85 I therefore particularly point out and distinctly claim as my invention:

90 1. Pumping apparatus comprising a casing providing a pump chamber, an inlet and an outlet for said chamber, pumping mechanism arranged in said chamber, said outlet comprising a storage branch, a service branch, and a fresh water branch all formed in said casing, a check valve mounted in said casing between said fresh water branch and said storage and service branches, and means for driving said pumping mechanism.

95 2. Pumping apparatus comprising a casing providing a pump chamber, an inlet and an outlet for said chamber, pumping mechanism arranged in said chamber, an electric motor for operating said pumping mechanism, said outlet comprising a storage branch, a service branch, and a fresh water branch, means to prevent flow of fluid from said storage and service branches into said fresh water branch, and a pressure responsive switch connected to said fresh water branch and adapted to make and break the electrical circuit for said motor.

100 Signed by me this 8th day of December, 1927.

105 GALE L. FERGUSON.
